Primary Examiner—Wallace R. Burke*Assistant Examiner*—Marcus Jackson*Attorney, Agent, or Firm*—Marvin L. Moore[57] **CLAIM**

The ornamental design for a illuminated hand-held stop sign, as shown and described.

DESCRIPTION

FIG. 1 is a perspective of the illuminated hand-held stop sign of our design;

FIG. 2 is a top view thereof;

FIG. 3 is a front view thereof wherein the opposite side appears the same except for the omission of the switch;

FIG. 4 is a bottom view thereof; and,

FIG. 5 is a left end view thereof with the opposite side being a mirror image.
